(57) **CLAIM**

The ornamental design for a conical buffing pad, substantially, as shown and described.

DESCRIPTION

FIG. 1 is a perspective view of a conical buffing pad, according to a first embodiment of the invention;

FIG. 2 is a side view of the conical buffing pad of FIG. 1;

FIG. 3 is a top view of the conical buffing pad of FIG. 1;

FIG. 4 is a bottom view of the conical buffing pad of FIG. 1;

FIG. 5 is a perspective view of a conical buffing pad, according to a second embodiment of the invention;

FIG. 6 is a side view of the conical buffing pad of FIG. 5; FIG. 7 is a top view of the conical buffing pad of FIG. 5; and, FIG. 8 is a bottom view of the conical buffing pad of FIG. 5.

The cylindrical tube protruding from the top of pad shown in FIGS. 5-8 is transparent and has a minimally thick wall. Any broken lines represent environmental structure and form no part of the claimed design.

1 Claim, 8 Drawing Sheets
